His Attorney.

UNITED STATES PATENT OFFICE

AMOS MADSON, OF PONTIAC, ILLINOIS, ASSIGNOR TO NORWAY WELT SHOE CORPORATION, OF WILMINGTON, DELAWARE, A CORPORATION OF DELAWARE.

DIE FOR SHOE SOLES.

1,418,317.

Specification of Letters Patent. Patented June 6, 1922.

Application filed May 7, 1920. Serial No. 379,498.

To all whom it may concern:

Be it known that I, AMOS MADSON, a subject of the King of Norway, and residing at Pontiac, in the county of Livingston, State 5 of Illinois, have invented the new and useful Improvement in Dies for Shoe Soles, of which the following is a specification.

This invention relates to dies and more particularly to dies for shoe soles.

10 One of the objects of this invention is to provide a die adapted to form a marginal recess at the heel of the sole in order to form the heel seat.

Another object is to provide a die adapted 15 to form not only a marginal recess at the heel but also a marginal lip along the sole part.

Further objects will appear from the detail description taken in connection with the 20 accompanying drawing, in which:

Figure 1 is a perspective view of a die embodying this invention;

Figure 2 is a bottom view showing the cutting edge;

25 Figure 3 is a perspective view of another die embodying this invention;

Figure 4 is a bottom view showing the cutting edge; and,

Figure 5 is a plan of the sole.

30 Referring now to the accompanying drawing, and more particularly to Figure 5, the shoe sole 1 is to be formed with a die embodying the invention as shown. This shoe sole has a marginal recess at the heel to 35 form a heel seat 2 of reduced width, while the fore part which forms the shoulders 3 will have a marginal lip or extension 4 for the attachment of the upper thereto.

Referring to Figures 1 and 2, the die 40 is provided with an arcuate part which is beveled inwardly to provide an inner cutting edge 11 and with outwardly extending parts which are beveled outwardly to provide outer cutting edges 12, the body of the die being recessed as shown at 13 so as to leave a bridge 14 connecting the outwardly extending parts and providing for strength of the die, at the same time leaving the desired cutting edge. This die is arranged to 45 be used in any suitable press, the leather to be cut being placed on the table and the die

being placed on the leather to be struck by the beam of the press. This form of die is adapted to be used more particularly for soles which have been previously died out 55 and this die, therefore, forms the marginal recess at the heel, the arcuate part 11 of the cutting edge forming the arcuate contour of the heel, while the outwardly extending parts 12 form the shoulders 3; these outwardly extending parts 12 are, of course, of sufficient length to sever completely through to the edges of the sole at the breast.

Referring now to Figures 3 and 4, the die 20 has a cutting edge comprising an arcuate 65 part 21 for the toe, an arcuate part 22 for the heel, web parts 23 connecting with the arcuate part 21, and outwardly extending parts 24 connecting the arcuate part 22 with the web part 23. This die is also arranged to 70 be used in an ordinary press but in this case is adapted for dieing out complete a sole from the hide or blocked out blanks. With this die, the arcuate part 21 and the web parts 23 will contour the fore part, the arcuate 75 part 22 will contour the heel, while the outwardly extending parts will form the shoulders 3. The die is, therefore, adapted to form a sole with the marginal recess at the heel and with a marginal lip extending 80 around the fore part.

It is obvious that various changes may be made in the details of construction without departing from the spirit of this invention; it is to be noted, therefore, that this invention is not to be limited to the specific details shown and described.

Having thus described the invention, what is claimed is:

1. A die for shoe soles, comprising, an arcuate part and outwardly extending parts at the ends of and integral with said arcuate part, said arcuate part being beveled inwardly to provide an inner cutting edge and said outwardly extending parts being beveled 95 outwardly to provide outer cutting edges.

2. A die for shoe soles, comprising, an arcuate part, outwardly extending parts at the ends of and integral with said arcuate part, and a bridge connecting said outwardly 100 extending parts, said arcuate part being beveled inwardly to provide an inner cutting

edge and said outwardly extending parts being beveled outwardly to provide outer cutting edges.

3. A die for shoe soles, comprising, an arcuate part, outwardly extending parts at the ends of and integral with said arcuate part, and a bridge connecting said outwardly extending parts, said arcuate part being bev-

eled inwardly to provide an inner cutting edge, said outwardly extending parts being beveled outwardly to provide outer cutting edges, and said bridge being recessed from the ends of said arcuate parts. 10

In testimony whereof I affix my signature this 5th day of May, 1920.

AMOS MADSON.
